BURNER FOR STEAM-AUTOMOBILES.

1,385,366.

Specification of Letters Patent. Patented July 26, 1921.

Application filed November 20, 1918. Serial No. 263,279.

To all whom it may concern:

Be it known that I, FRANCIS I. DU PONT, a citizen of the United States, residing at 5 Wilmington, county of New Castle, and State of Delaware, have invented a new and useful Improvement in Burners for Steam-Automobiles, of which the following is a full, clear, and exact description, reference being had to the accompanying drawings, 10 which form a part of this specification.

In the operation of gasolene or kerosene burners for steam automobiles, considerable time, skill, judgment and care are required to initially heat the burner. For 15 this purpose a pilot light is provided. The same comprises a small burner, a small mixing tube, a small fuel jet and a relatively short vaporizing tube connected with a supply of gasolene maintained at a pressure of 20 (say) thirty pounds to the square inch. The pilot light burner is so located that it heats both its own vaporizer and a portion of the end of the main vaporizer.

The pilot light burner performs two main 25 functions. First, it serves to initially ignite the main burner; secondly, it relights the main burner every time the automatic mechanism operated by the steam pressure cuts off the main fuel supply and turns it on 30 again. The pilot light burner, in performing the second function, operates quite satisfactorily; but where both burners are extinguished and it is necessary to ignite the main burner initially by first lighting the 35 pilot light burner, much difficulty is experienced in proceeding in such a way as to avoid trouble. The customary procedure is to heat the jet of the pilot nearly red hot with a small gasolene or acetylene torch, 40 then to turn on the gasolene supply for the pilot, and then to light the pilot through a small peep hole in the fire pan, which is then closed by a little shutter. It is then necessary to wait until the flame from the 45 pilot light sufficiently heats the end of the main vaporizing coil, so that the main fuel supply may be turned on. If good judgment is used, the burner starts properly. If, however, anything is done irregularly, 50 troublesome conditions arise. For example, if the main fuel supply is turned on before the pilot has sufficiently heated the small portion of the main vaporizing coil immediately over it, a certain amount of liquid fuel is injected into the mixing tubes of the

main burner. If, then, it be discovered that the pilot light is not working properly, and it is necessary to reheat it, the fact that this has to be done in close proximity to the jets and mixing tubes of the main burner will 60 almost certainly cause the liquid fuel which has collected there to catch fire; and then as long as any fire exists underneath the burner, it is impossible to start, because the gasified fuel will take fire in the mixing tube 65 instead of in the furnace. It is, therefore, necessary to use great caution, and to acquire considerable skill, in starting the furnace. Otherwise, a great delay will result, 70 as well as possible clogging up of the burner with lamp-black.

The object of my invention is to eliminate all the troubles attendant upon initially starting the burner. It is a further object of the invention to expedite the starting of the burner by permitting the fuel supply to be turned on immediately after the application of the external heating or flame-producing agency. A further object of the invention is to start the main burner independently of the pilot light burner and to limit the functions of the latter to the re-ignition of the main burner when, during operation, the main fuel supply is temporarily interrupted by the action of the automatic mechanism controlled by the steam pressure, and to maintaining a part of the main vaporizing coil hot enough to facilitate quick starting when the pilot light is left burning. A further object of the invention is to insure the proper starting of the burner after the application of the external heating agency, whether the fuel supplies to both burners are turned on quickly 80 or tardily, or whether they are turned on together, or whether either one is turned on before the other, thereby much reducing the time required to start the burner and removing, as factors essential to successful starting, the elements of care, skill and judgment. 85

It will be appreciated that the successful attainment of these objects removes one of the most serious objections to automobiles of the steam type.

I attain the objects above enumerated by a construction of great simplicity. A preferred embodiment of the invention is shown in the accompanying drawings, in which—

Figure 1 is a plan view; Fig. 2 a front 110

elevation; and Fig. 3 a side elevation of the complete burner. Fig. 4 is a cross-section on line 4—4 of Fig. 1.

The fire pan *a* is shown as of the usual construction, packing *b* of asbestos or clay extending along its peripheral wall. The main burner plate *c* is a thin iron casting provided with a great number of very small holes. The main fuel vaporizing coil *d*, 10 leading from a supply of kerosene or other hydrocarbon fuel, extends over the burner and terminates outside the fire pan. From a point near the forward terminus of the coil *d* short pipes *e* and *f* of relatively small 15 diameter communicate respectively with fuel jets *g* and *h*. The mixing tubes *i* and *j* extend from in front of the fuel jets horizontally beneath the burner *c*.

The pilot light burner comprises a small 20 chamber *k* provided with openings, preferably slotted, a small mixing tube *m*, and a small fuel jet *n*, the latter being connected, through a tube *o*, with a vaporizing tube *p*, which extends, for a short distance, over the 25 burner *c* and also over the burner *k*. The tube *p* is connected with a supply of gasoline maintained at approximately thirty pounds to the square inch pressure.

The construction of my improved burner, 30 so far as it has been described, exhibits no element of novelty. I shall now describe the improvement which I have applied to the known burner.

The ends of the two vaporizing tubes *d* 35 and *p* projecting outside of the furnace are inclosed within a tubular chamber *r*, whose interior is in free and open communication with the interior of the furnace and whose outer extremity projects beyond the extremities of the vaporizing tubes *d* and *p*. The small pipes or tubes *e*, *f* and *o*, leading to the jets *g*, *h*, and *n*, extend through the tube *r* with brazed, flame-tight joints. The outer end of the tube *r* is provided with a 45 cap *s* having an opening adapted to be closed by a swinging shutter *t*.

With my improvement, assuming that both the main burner and the pilot burner are extinguished, all that is required to start 50 the burners is to proceed as follows: The shutter *t* is swung open and a flame from a gasolene blow-torch *x*, or any other flame-projecting device, is directed through the opening in the cap *s* into the interior of the tube *r*. The flame envelops the ends of both 55 vaporizing tubes and the pipes are heated so quickly that almost immediately the supply of fuel for the main jet and pilot light may be turned on, and it is immaterial which one is turned on first. As soon as the burner has 60 started, the blow torch is withdrawn and the cap *s* is closed.

The invention presents the following advantages over the means commonly employed to start the burner,

It is not necessary to heat and start the pilot light preliminarily to initially igniting the main burner, the only necessary functions of the pilot light being to start the main burner when the automatic mechanism operated by steam pressure cuts off the main fuel supply and turns it on again and to maintain a part of the vaporizing coil hot enough to facilitate quick starting.

The loss of time, heretofore incurred in 75 the initial lighting of the burner, due to waiting until the pilot light sufficiently heats the end of the main vaporizing coil, is avoided.

It is unnecessary for the operator to use 80 the care, judgment and skill heretofore required to determine when the pilot light is sufficiently heated and in turning on the main fuel supply at just the proper time.

Since the opening through which the flame 85 is projected is sufficiently distant from the fuel jets, it is possible to apply the flame any time without danger of igniting the fuel issuing from the jets.

Even if a collection of liquid fuel accidentally occurs in the burner, there is no 90 danger of setting this on fire when heating the vaporizing coils preparatory to starting.

The troubles arising from failure to exercise care and judgment in starting are 95 avoided for two reasons. First, since a powerful flame can be injected along the vaporizing tubes themselves, they become heated at once; and second, even if the fuel should be turned on before they are quite 100 heated, no trouble results, as the flame is not near the fuel jets, but, instead, is where it serves to ignite the mixed fuel as it issues from the burner.

The ends of the vaporizing tubes are kept 105 hot by reason of the tube *r* being in communication with the interior of the furnace.

Having now fully described my invention, 110 what I claim and desire to protect by Letters Patent is:

1. In a hydrocarbon fuel burning apparatus for steam automobiles, the combination with the furnace, of a burner plate within the furnace, and a vaporizer within the furnace and having a portion extending to the exterior thereof and adapted to be heated either by means of said burner plate or by external means, there being an opening to permit said heat by external means so placed that the flame used in said external heat will 115 also serve to ignite the main burner as soon as fuel is turned on.

2. In a hydrocarbon fuel burning apparatus for steam automobiles, the combination with the furnace, of a main burner and a pilot light burner within the furnace, a main fuel jet in operative relation with the main burner plate, a fuel jet in operative relation with the pilot light burner plate, and fuel supply tubes leading to the respec- 120 125 130

- tive jets and positioned and arranged to be heated either by the respective burners or by externally applied heating means between the jets and the parts of the tubes in operative relation with the burner plates.
3. In a hydrocarbon fuel burning apparatus for steam automobiles, the combination, with the furnace, of a main burner plate, a vaporizer adapted to be heated by the main burner plate, a main fuel jet, a pilot light burner plate, a vaporizer adapted to be heated by the pilot light burner plate, both of said vaporizers having portions on the exterior of the furnace, and a pilot light fuel jet, and provisions for heating said portions of the vaporizers on the exterior of the furnace by external means so positioned and arranged that the external heat will also serve to ignite the main burner as soon as the main fuel jet is rendered operative.
4. In a hydrocarbon fuel burning apparatus for steam automobiles, the combination, with the furnace, of a main burner plate and a pilot light burner plate, both within the furnace, fuel jets in operative relation with the respective plates, fuel supply tubes leading to the respective jets, and an inclosure through which said tubes extend, said inclosure having openings, one in proximity to said plates and the other for admission of an external ignition agent, both said jets being located outside said inclosure.
5. In a hydrocarbon fuel burning apparatus for steam automobiles, the combination, with the furnace, of a main burner and a pilot light burner comprising fuel jets and fuel supply tubes leading through and out of said furnace to said jets, a chamber inclosing those parts of the fuel supply tubes which lead out of said furnace but not inclosing either of said jets, said chamber having an opening through which a flame may be projected to heat the fuel supply tubes inclosed within said chamber and to ignite both the main burner and the pilot light burner.
6. In a hydrocarbon fuel burner for steam automobiles, the combination, with a furnace, of a main burner plate and a pilot burner plate within the furnace, mixing tubes extending into the respective burner plates, a heating chamber opening into the furnace, and adapted for the admission of externally produced heating and ignition means, fuel jets outside the furnace and the heating chamber and in operative relation with the respective mixing tubes, fuel supply tubes in operative relation to the respective burner plates and extending into said heating chamber, and connections from said tubes to the external fuel jets.
7. In a hydrocarbon fuel burning apparatus for steam automobiles, the combination with the furnace, the main burner plate, and the main fuel jet and mixing tube associated therewith, the pilot light burner plate and the fuel jet and mixing tube associated therewith, the main fuel vaporizing tube and the auxiliary fuel vaporizing tube, said tubes extending side by side outside the furnace, of a preliminary-heating chamber opening into the furnace and inclosing the portions of said tubes extending outside the furnace, and tubular connections between the inclosed portions of the tubes and the respective jets, said tubular connections extending through the wall of the heating chamber with flame-tight joints.
8. In a hydrocarbon fuel burning apparatus for steam automobiles, the combination with the furnace, a main burner and a pilot light burner and fuel jets and fuel supply tubes leading through said furnace and out of same to said jets, of means to project a flame from external sources upon part of said fuel tubes within said furnace while maintaining said projected flame out of communication with both fuel jets.
9. In a hydrocarbon fuel burning apparatus for steam automobiles, the combination with the furnace, a main burner, a pilot light burner, fuel jets and fuel supply tubes leading through said furnace and out of same to said jets, of a heating chamber inclosing that part of the fuel tubes which emerge from the furnace, said chamber being in communication with the interior of the furnace, said chamber also having an opening through which a flame may be projected along that part of the fuel tubes which extend from the furnace into the chamber, said opening being at a distance from the fuel jets sufficient to be safe against ignition of both said jets.
10. In a hydrocarbon fuel burning apparatus for steam automobiles, the combination with the furnace, of a main burner plate and a pilot burner plate within the furnace, mixing tubes extending in the furnace adjacent to the respective burner plates and opening outside the furnace, fuel jets outside the furnace in front of the respective mixing tubes, vaporizer tubes within the furnace extending adjacent to the respective burner plates, a heating chamber extending outside the furnace, with its inner end opening into the furnace and its outer end having an opening through which a flame may be projected along the length of the chamber, said vaporizing tubes being prolonged to extend inside the heating chamber, and pipe connections extending from those parts of the vaporizing tubes within the heating chamber to the outside of the furnace and there connected with the respective fuel jets.

In testimony of which invention, I have hereunto set my hand, at Wilmington, Delaware, on this 19th day of November, 1918.

FRANCIS I. DU PONT,
